WARNING LIGHT

Lyle D. Atkins, 655 W. Olmos, and Chester M. Norton,
446 Pilgrim, both of San Antonio, Tex.

Filed Aug. 20, 1962, Ser. No. 71,368

Term of patent 14 years

(Cl. D72—1)

FIG. 1 is an isometric view of a warning light showing our new design; and

FIG. 2 is an isometric view thereof taken diametrically opposite and below the position shown in FIG. 1.

We claim:

The ornamental design for a warning light, substantially as shown.
